CULINARY ARTICLE

Nathan Bell, Los Angeles, Calif.

Application January 13, 1936, Serial No. 58,812

2 Claims. (Cl. 146—170)

This invention relates to culinary articles, and is more particularly directed to new, novel and improved means for slicing fresh string beans and has for certain of its essential objects to provide a simple and inexpensive device of this character adapted to be clamped upon the edge of a table top or suitable support in a manner to dispose the cutting knives in the direct path of downward insertion of the bean through a bean guide and enable one end of the bean to be pulled by hand across the knives to thereby cut the bean into a plurality of sections or substantially identical strips; the manner of mounting the bean guide and the knives serving further to greatly facilitate the slicing operation and enable same to be deposited into a receptacle as readily as the slicing operation proceeds.

With the above mentioned and other objects in view, the invention consists in the novel construction and combination of parts hereinafter described, illustrated in the accompanying drawing, and set forth in the claims hereto appended, it being understood that various changes in the form, proportion, size and minor details of construction within the scope of the claims may be resorted to without departing from the spirit or sacrificing any of the advantages of the invention.

In the drawing,

Figure 1 is a plan view of the device showing same applied to the top of a table;

Figure 2 is a vertical longitudinal section on line 2—2 of Figure 1;

Figure 3 is a horizontal section on line 3—3 of Figure 2;

Figure 4 is a vertical section on line 4—4 of Figure 2;

Figure 5 is a perspective view of the blade holder;

Figure 6 is a view similar to Figure 1 of a modified form of the invention;

Figure 7 is a vertical section on line 7—7 of Figure 6;

Figure 8 is a perspective view of the bracket employed in the modified form of the invention.

In the form of my invention disclosed in Figures 1 to 5, inclusive, use is made of a clamp having resilient jaws 10 and 11 of flat metal adapted to be attached to a table top T or like support to dispose the flat lateral extension 12 of the clamp in a horizontal position as clearly shown in Figures 1 and 2.

The extension 12 has a vertical, rectangular opening 13 passing therethrough and as shown in Figure 4 said opening is formed by merely slitting the material of the extension and striking

from the latter the parallel disposed vertical flanges 14—14, the lower ends of which are bent angularly to provide stops 14a.

The extension 12 constitutes a holder for a combined bean guide and knife carrier 15, insertable into the opening 13 into engagement with the stops 14a. Mounted in said guide which is in the form of an open-ended sleeve, and disposed diagonally relative to the axis of the opening are leaf springs 16—16 to resiliently grip the bean and center same in the guide. The outer ends 17 of said springs are preferably, but not necessarily, passed into the opening 13 to be confined between the end walls thereof and the adjacent walls of the guide. The lower end of said guide is provided with a suitable number of cutting blades 18, disposed in parallel spaced relation to each other and having continuous sharp cutting edges 19. These knives are thus mounted so as to be directly located in the path of a bean to thereby cut same into equally proportioned long length strips or sections.

The operation will be readily understood on reference to Figure 2 of the drawing, wherein a string bean B is shown passing through the combined guide and knife carrier. It need only be said that to cut the bean, one end thereof is inserted in the guide and pushed downwardly to pass the knives 18, after which the bean can be grasped between the fingers from beneath the knives and the bean pulled downwardly to complete the cutting operation.

In the form of the invention shown in Figures 6 to 8, inclusive, the clamp preferably consists of a body portion struck from a single blank of flat spring metal to provide upper and lower clamping jaws 20 and 21 and a vertical connecting portion 22. To the portion 22 is riveted or otherwise suitably secured at 23 a vertically disposed stirrup or yoke 24 which functions to receive a knife carrier and bean guide 25. This guide may be cast from metal or any suitable well known composition of matter, and same is provided with a vertical ovate opening 26 through which the bean can move and be sliced by the knives 27 at the lower end of said opening. The lower end of the guide is removably supported by the lugs 28 formed of the lower edges of the oppositely disposed walls of the yoke 24.

I do not wish to limit myself to the precise form of device herein illustrated and shall have it clearly understood that the essence of the invention resides more particularly in the form of a means adapted to be readily clamped to and removed from a support, such as a table top, 50

whereby to dispose the bean guide and knife carrier in a vertical position at one side of the table. This feature will be broadly claimed, and I shall emphasize the importance attached to the provision of a cutter against which a bean can be severed initially by a pushing action imposed thereagainst and the operation completed by pulling the partially cut bean through the guide and across the knives to thereby complete the cutting operation.

10 What is claimed is:

1. A culinary article comprising rectangular open-ended sleeve having spaced cutting blades for cutting into strips, a string bean forced through said sleeve; a holder having an opening to receive the sleeve; yieldable flanges projecting from the holder between which the sleeve is forced and is frictionally retained against withdrawal from the opening; means on the flanges with

which the sleeve co-acts to definitely limit the extent to which the sleeve can be inserted; and means by which the holder can be attached to a support.

2. A culinary article comprising an open-ended sleeve having spaced cutting blades for cutting into strips, a string bean forced through said sleeve; a holder having a horizontal opening to vertically receive the sleeve; depending spring flanges projecting from opposed walls of the opening and normally occupying a contracted position to be expanded by and frictionally grip the sleeve against upward displacement from the opening; stop flanges projecting inwardly from the aforesigned flanges, against which the lower end of the sleeve abuts to provide a seat for the sleeve; and means by which the holder can be attached to a support.

NATHAN BELL.
